UNITED STATES PATENT OFFICE.

FRANCIS C. MASON, OF GRAND RAPIDS, MICHIGAN, ASSIGNOR TO THE BISSELL CARPET SWEEPER COMPANY, OF GRAND RAPIDS, MICHIGAN, A CORPORATION.

ROLLER-BEARING FOR CARPET-SWEEPERS.

SPECIFICATION forming part of Letters Patent No. 709,444, dated September 16, 1902.

Application filed October 30, 1901. Serial No. 80,554. (No model.)

To all whom it may concern:

Be it known that I, FRANCIS C. MASON, a citizen of the United States, residing at Grand Rapids, in the county of Kent and State of Michigan, have invented new and useful Improvements in Roller-Bearings for Carpet-Sweepers, of which the following is a specification.

My invention relates to certain new and useful improvements in roller-bearings for carpet-sweepers; and the invention consists in combining with the driving-wheels of the carpet-sweeper a series of antifriction-rollers arranged in the hub of the sweeper and between the hub and the journal of the driving-wheel axle, also in means hereinafter shown and described for retaining the rollers in position in the hub of the wheel.

The objects of my invention are, first, to furnish a cheap and efficient roller-bearing for a carpet-sweeper; second, to furnish suitable means for retaining the rollers in the hub of the carpet-sweeper; third, to facilitate the insertion of the rollers in position in the hub of the carpet-sweeper. These objects I accomplish by means of the mechanism illustrated in the accompanying drawings, in which—

Figure 1 shows an end elevation of the carpet-sweeper constructed in accordance with my invention. Fig. 2 shows a plan view of a portion of the carpet-sweeper, one of the driving-wheels shown in section.

Like letters refer to like parts throughout the several views.

A represents the carpet-sweeper case, which may be constructed of wood or any suitable material and of any suitable shape.

B B show two of the driving-wheels at the end of the case.

C C, &c., show the antifriction-rollers.

In Fig. 1 the rollers are shown in the position in the hub of the wheel, the elastic retaining-strip being cut away in order to show the position of the wheel, the hub, and the antifriction-rollers.

D shows the driving-wheel axle.

The spring-guard is shown by E, which in the example of my invention shown in the drawings extends across the end of the case

and in close proximity to the hubs of the driving-wheels.

F is the support for the bearings of the brush-roller.

G is the brush-roller, and I is the frictional 55 pulley on the brush-roller, which engages with the peripheries of the driving-wheels B B.

J is a washer between the hub of the driving-wheel and the case. This washer J may be secured to the hub so as to revolve with 60 it and in that way become a part thereof. Instead of securing the washer J to the hub, however, it may be secured to the case or may be left as a loose washer between the hub and the case. This washer furnishes a guard 65 which prevents the rollers C C, &c., from being driven too far toward the sweeper-case. Thus it holds the rollers in position at one end of the hub. The elastic guard E passes in close proximity to the outer end of the hub 70 of the driving-wheel and serves to retain the rollers in proper position within the hub.

H is the bail-support for the carpet-sweeper.

With the construction above described I am enabled to bore the opening in the hub 75 entirely through, if desired, and to insert the rollers of preferably uniform size into the hub and around the axle D. This greatly facilitates the construction of the carpet-sweeper roller-bearings and enables me to use 80 these rollers in a hub which is solid and made integral with the wheel itself. If desired, the washer may be applied at the outer end of the hub and between the outer end of the hub and the spring-guard E. This construction is adapted to all kinds of carpet-sweepers and to wheels of iron or other suitable metal where it is desired to apply a roller-bearing without the necessity of making the hub in two or more sections.

Having thus described my invention, what I claim to have invented, and desire to secure by Letters Patent, is—

The combination of a casing having a driving-wheel, an axle carried by the casing and 95 extending through the hub of said driving-wheel, and the hub extending outward beyond the rim of the wheel, a series of antifriction-rollers in the hub bearing against said axle, a guard on the casing crossing the 100

outer open end of the hub and adapted to directly engage the outer ends of said rollers to thereby prevent outward displacement of the same and to also hold the wheel on its axle, 5 and independent means for preventing inward displacement of said rollers.

In testimony whereof I have hereunto set

my hand in presence of two subscribing witnesses.

FRANCIS C. MASON.
